BACK REST FOR BEDS

Brooks E. Rogerson, Chagrin Falls, Ohio

Application January 7, 1943, Serial No. 471,531

1 Claim. (Cl. 5—71)

This invention relates to an improved form of adjustable back-rest for use in a bed, my device being in the form of a separate accessory which can be readily placed in any conventional form of bed and readily removed therefrom.

I am aware that there have already been devised adjustable back-rests to be placed upon the outside of the bed or upon the floor, and that means have been built into as a permanent part of a bed for affording adjustable support for the back of the user while occupying the bed. Then, too, there have been devised similar arrangements involving specially constructed springs or mattresses.

But the object of my invention is to devise a back-rest in the form of an accessory which can be placed between the conventional springs and mattress of a bed without any modification thereof and can be readily adjusted by the user, while occupying position in the bed, so as to provide the inclination desired for the back.

Another object is to provide such a device that is so constructed and arranged that it can be collapsed into substantially flat condition for storage or shipping, the locking means therefor being readily removable for this purpose.

Another object is to provide such a device of skeleton or frame construction with means for properly supporting the mattress when in inclined position and at the same time for affording comfortable, self-accommodating condition thereof for the back of the user.

Another object is to provide such a device with a locking member of a form corresponding substantially with the arc of movement of the adjustable member, so as to more efficiently house the locking member during all positions of adjustment and also to provide more efficient locking engagement thereof.

Other objects will appear from the following description and claims when considered together with the accompanying drawings.

Fig. 1 is a side view of my device in collapsed or idle position within a bed;

Fig. 2 is a side view of my device in raised or active position within a bed;

Fig. 3 is a plan view of my device in raised position;

Fig. 4 is a bottom plan view of a part of the locking means embodied within my device;

Fig. 5 is a view taken on line 5—5 of Fig. 3; and

Fig. 6 is a view taken on line 6—6 of Fig. 2.

It is to be understood that the present form of disclosure is merely for the purpose of illustration and that there might be devised various

modifications thereof without departing from the spirit of my invention as herein set forth and claimed.

The lower member 1 is of skeleton form, consisting of angle metal strips along the three sides thereof and being open at the front thereof. This member is reinforced by the angle strips 2 and 3. The upper member 4 is of like construction and comprises the angle metal strips along the three sides thereof, with its front side open. The upper member 4 is reinforced by means of the angle strips 5 and 6. The upper member is pivotally connected to the lower member at the front corners thereof, as indicated at the points 7 and 8, the upper member being arranged within the lower member so that it can occupy folded or idle position therewithin, thereby rendering the same very compact for storage or shipping.

As indicated in Figs. 1 and 2, the pivotally connected members 1 and 4 are adapted to be placed between the regular bed springs S and the regular mattress M, neither of which is required to be modified at all in order to accommodate this device and to permit of its manipulation in the manner to be described. As shown in Fig. 2, the member 4 is adapted to be raised to inclined position, to the extent desired, so as to support the head portion of the mattress in such position, as herein indicated, and thereby afford comfortable sitting or reclining position for the user while in bed.

In order to hold the member 4 in the inclined position desired, I have provided the locking device which is of bail form and is pivotally mounted at the points 9 and 10 upon the rear part of the upper member 4 so as to be manipulatable about a horizontal axis by means of the transverse handle 11 at the upper part thereof. For this purpose, each of the two sides 12 and 12' of the locking member has affixed thereto an outwardly projecting pin, as indicated at 9 and 10, for removable engagement outwardly in the corresponding holes in the struts 13 and 14 which are mounted upon the upper part of the member 4 and to which the ends of the reinforcing members 5 and 6 are connected. The lower ends of the sides 12 and 12' are connected by the transverse bar 15 which is removably connected thereto by means of the nuts 16 which hold the side parts 12 and 12' against the inner nuts 17 and 18 on the bar 15. Thus, when the bar 15 is removed, the side parts 12 and 12' can be sprung inwardly sufficiently to permit the pins 9 and 10 to be withdrawn from their holes and the locking member entirely removed. Then, when

it is desired to assemble the locking member, the reverse procedure will be followed; that is, the pins 9 and 10 will first be inserted outwardly through the holes, this being permitted by springing the side parts 12 and 12' inwardly, whereupon the bar 15 will be placed in position so as to hold the side parts 12 and 12' in spread position and thereby prevent removal of the pins 9 and 10 so long as the bar 15 occupies such position. The side parts 12 and 12' are each provided with the ratchet teeth 19 and 20 which are adapted for engagement with the edge portions of the rear angle bar of the lower member 1, as indicated in Fig. 5. The side parts 12 and 12' extend through the keepers 21 and 22 which are secured to the underside of the rear part of the lower member 1, as also seen in Fig. 5. These keepers prevent the side parts 12 and 12' from swinging too far rearwardly away from the locking edges; and also they will be engaged by the bar 15, when the upper member is in extreme raised position, so as to prevent removal of the side parts 12 and 12' from their assembled position within the keepers 21 and 22.

As indicated in Figs. 1 and 2, the side parts 12 and 12' are curved in a manner corresponding substantially with the arc described by the upper member 4 during its adjustable movement, thereby the more efficiently accommodating the locking member to the space between the head of the bed and the springs and mattress. It is to be understood that the springs and mattress will be pulled away slightly from the head of the bed, upon installation of this device, and this comparatively small space will be sufficient to accommodate the manipulation of the locking member. Upon the rear part of the lower member 1 there may be provided a strip of felt or other suitable material for engagement with the head of the bed so as not to mar the same when the device is in operative position, as herein indicated by reference numeral 1'.

Extending between the reinforcing angle strips 5, I have provided a plurality of resilient light metal straps 23 which are connected thereto by means of pairs of coil springs 24, the purpose of this provision being to maintain the corresponding part of the mattress in proper position so as not to sag under the weight of the user and at the same time to permit comfortable self-accommodation of the mattress to the back of the user as he rests thereagainst.

At the front of the back-rest, there is attached thereto in any suitable manner an apron of canvas or other appropriate material, as indicated by reference numeral 25, it being intended that the weight of the user upon this apron, as he occupies position in bed, will serve to hold the device in proper position at all times of use or non-use. In the present form of illustration, I have shown a rod 26 extending across the front end of the back-rest and being connected thereto and having the apron 25 attached thereto.

Assuming that the back-rest occupies idle position, as indicated in Fig. 1, and assuming that it is desired to raise the upper part 4 of the device to inclined position, even while the user occupies position in the bed. This may be done by the user merely assuming sitting position in bed, grasping the handle 11 of the locking device and pulling upwardly upon the same so as to raise the upper member 4 and the mattress therewith. When the mattress has been raised to the desired angle, the back-rest may be locked in such set position by turning the locking device about its

pivotal axis in a clock-wise direction, as viewed in Fig. 2, so as to bring the ratchet teeth 19 and 20 into the path of their companion edges for engagement therewith, which is accomplished by permitting the upper member 4 and the locking member to be lowered sufficiently to effect such locking engagement. Then, when the user rests his weight against the inclined member 4, this will serve to hold the locking member in effective engagement so as to hold the upper member 4 in the inclined position to which it has been adjusted. When it is desired to release the locking member and to lower the back-rest to a lower position or to completely idle position, this may be done by the user moving the upper part of his body away from the inclined part of the mattress and then grasping the handle 11 and pressing against the same so as to turn the locking member in a counter-clockwise direction about its pivotal axis, as viewed in Fig. 2, so as to release the ratchet teeth from engagement, and then lowering the upper part 4 of the device with the corresponding part of the mattress, while holding the locking member in the same released position until the back-rest has been lowered to the point desired.

As indicated in Figs. 1 and 2, the handle 11 of the locking member occupies position sufficiently above the top of the mattress to be readily accessible to the hand of the user, it being understood that this slight projection of the handle above the mattress will be completely and effectively covered by the usual pillows at the head of the bed. In fact, the entire device is completely out of sight while installed in a bed and when not in use. Even when the device occupies raised position, it will not be at all noticeable except at the side of the bed and this is not objectionable as it is not at all unsightly.

Thus I have devised an adjustable back-rest which can be very readily placed in a bed or removed therefrom without involving any change whatever in the bed or any part thereof and without involving any additional mechanism; and there is nothing unsightly about it at any time. Also, it can be manipulated by the user while in bed and it will always ensure complete comfort to the user in all positions. Furthermore, this device is of a comparatively simple form of construction, there is nothing to get out of order over a prolonged period of time, and it can be manufactured and sold at a very popular price and installed and used without any additional expense. This same device can be employed with equal efficiency in a home or a hospital.

What I claim is:

A back-rest for a bed, in the form of a self-contained accessory adapted to be removably placed between the springs and mattress of the bed and comprising a lower part to be supported upon the springs and an adjustable upper part to support the mattress in the desired inclined position, said upper part being pivotally connected at the lower end thereof to the front end of said lower part so as to be adjustable about a horizontal axis for raising and lowering the same, said upper and lower parts being separate from the bed and being of substantially plain flat form throughout and being connected directly to each other so as to lie substantially flat throughout when the upper part is in fully lowered position, and a substantially U-shaped locking member having resilient arms pivotally mounted upon the rear part of said upper member for movement about a horizontal axis, said U-shaped member having pins projecting laterally from opposite

arms thereof, apertures in portions of said upper member receiving said pins, releasable rigid means extending between the arms of said locking member so as to hold the same in such pivotal engagement, the arms of said U-shaped locking member being movable laterally upon release of said rigid means for effecting engagement or disengagement of said pins, whereby the locking member may be removed and placed in substantially flat condition

with the other parts for shipping or storage, and said locking member having means for releasable locking engagement with the rear part of said lower member and having an upwardly extending handle portion readily accessible for manipulation by the hand of the user while occupying position in the bed.

BROOKS E. ROGERSON.
